US0D1084229S

(12) **United States Design Patent** (10) **Patent No.:** **US D1,084,229 S**
(45) **Date of Patent:** **** Jul. 15, 2025**

(54) **VENTURI SIGNAL AMPLIFIER**

(71) Applicant: **Karl Dungs GmbH & Co. KG**,
Urbach (DE)

(72) Inventor: **Joachim Forster**, Winnenden (DE)

(73) Assignee: **KARL DUNGS GMBH & CO. KG**,
Urbach (DE)

(**) Term: **15 Years**

(21) Appl. No.: **29/844,745**

(22) Filed: **Jun. 30, 2022**

Related U.S. Application Data

(62) Division of application No. 29/713,874, filed on Nov.
19, 2019, now Pat. No. Des. 960,321.

(57) **CLAIM**

The ornamental design for a venturi signal amplifier as shown and described.

DESCRIPTION

FIG. 1 is a front perspective view of a venturi signal amplifier showing my new design;

FIG. 2 is a front elevation view thereof;

FIG. 3 is a rear elevation view thereof;

FIG. 4 is a rear perspective view thereof; and,

FIG. 5 is a cross-sectional view taken in the direction of line 5-5 of FIG. 4.

(Continued)

The broken lines shown in the drawings and the lower opacity areas within the broken lines depict portions of the venturi signal amplifier that form no part of the claimed design.

1 Claim, 4 Drawing Sheets
